UNITED STATES PATENT OFFICE.

JAMES E. WELTON, OF WOODSVILLE, NEW HAMPSHIRE.

SHUTTLE.

SPECIFICATION forming part of Letters Patent No. 775,589, dated November 22, 1904.

Application filed May 18, 1904. Serial No. 208,575. (Model).

To all whom it may concern:

Be it known that I, JAMES E. WELTON, of Woodsville, in the county of Grafton and State of New Hampshire, have invented certain new and useful Improvements in Shuttles, of which the following is a specification.

My invention relates to shuttles used in textile weaving, and is intended to provide a means whereby the bobbin or cop may be threaded to the shuttle by the use of the hands only without the assistance of suction or of any kind of hook.

The shuttles in most common use are provided with a recess or chamber in which is the bobbin or cop and an eye which pierces the side of one end of the shuttle into the end of said recess or a continuation thereof. This eye or eduction-tube is too small for the insertion of the fingers, and the usual method of threading is to present a bight or loose end of filling from the cop or bobbin to the inner end of the eye, and then by bringing the outer end to the lips and drawing in the breath the end is sucked through. The objection to this suction method is that filaments of fiber are drawn with the breath into the mouth and lungs and that with many colored yarns the dye gets onto the shuttle, the lips, and into the mouth. The fiber and dye thus coming in contact with mucous membranes are very unhealthy, and the contact of the lips of different operatives with the same shuttle is very likely to carry contagion and disease.

My invention provides a threader which can be used with great speed and wherein the bight of thread can be picked out easily by the thumb and forefinger of the operator without wetting either.

The invention is shown in the accompanying drawings, in which—

Figure 1 is a top view of the shuttle, showing the first position of the filling. Fig. 2 is a partial cross-section at line *w x* and shows the second position of the filling. Fig. 3 is a view similar to Fig. 1, but with a portion of the wood cut away to show the thread-guide and the filling as it slides down the guide. Fig. 4 is a side view showing the last position of the thread. Fig. 5 is a partial cross-section at line *y z*, showing the way the

guide and filling protrude into a recess from which the filling can be readily picked out by the thumb and forefinger. Figs. 6 and 7 show modifications of the gooseneck and eduction-tube outlet. Fig. 8 shows the preferred form of eduction-tube outlet and tang.

The cop or bobbin chamber *a* is extended in the form of a narrow slot *b* toward the end of the shuttle from which the filling is to be fed. A substantially oval or oblong chamber *c* extends from the bottom of slot *b* through the outer side wall of the shuttle.

The thread-guide *k* consists of a sheet of brass or other suitable metal bent at one end into nearly a complete cylinder or tube *d*, which forms the eduction-tube or shuttle-eye. This cylindrical portion *d* fits snugly into the end of chamber *c* which is nearer the cop or bobbin chamber *a* and is held in place either by friction (being driven in) or by a pin *e*, driven through the wood of the shuttle and said cylinder, as shown in Fig. 2. The inside edge of this thread-guide *k* is substantially straight and runs near the wall of slot *b*, but without touching it. The outer edge forms a curve or line at an oblique angle to the axis of the shuttle (see Fig. 3) from the outside of the shuttle, running forward, of such a shape that the portion nearest the outside of eduction-tube *d* is nearer the inside end of said tube than is the inner end of said edge. The curved portion and the straight portion of the thread-guide must easily clear the upper and lower walls of the chamber *c* and run together inside slot *b* into gooseneck *f*, which rises at an oblique angle to the other portion and to the axis of the shuttle until almost out of the slot *b*, when it is curved forward in a plane nearly parallel with the axis of the shuttle and forms the pointed head *g*. The point of this head *g* nearly touches the wall of slot *b* which is farthest from tube *d* and is provided with a tail or tang *h*, which slopes backward and outward toward the outlet of tube *d*. By this construction the thread can be passed by the head on one side only and cannot get back on the same side, but must form a loop over the gooseneck.

The end of tail *h* projects into a recess *i*,

cut in the wall of slot *b* which is nearer the tube *d*, whereby as the filling is brought forward by the hand it must always be deflected around the same side of head *g*, and as it is again brought back it passes by the end of tail *h* and is thereby prevented from slipping off the end of gooseneck *f*. At the points where gooseneck *f* joins head *g* and the body of thread-guide *k* it should form tangential curves, and the curved edge of thread-guide *k* should form a reverse tangential curve with the side of gooseneck *f* of such a radius that the filling will not catch at that point.

The curved outer edge of thread-guide *k* ends in a tang *l*, which runs down and across the slot and opening of tube *d* into a suitable recess *m*, cut in the wood.

The better form of outlet for eduction-tube *d* is that shown in Fig. 8. In this case an oval hole *v* is punched at the point where tang *l* joins the body of guide *k*, whereby when the thread finally reaches tube *d* it bears against the curved side of this hole instead of against the V-shaped bearing. (Shown in Figs. 3 and 4.)

The purpose of tang *l* is to allow the filling to be passed into tube *d* and to prevent its getting out when once in.

An oval recess *n* is cut in the side of the shuttle about chamber *e* and guide *k*, whereby the forefinger and thumb may grasp the thread at the point where it finally rests upon guide *k*, as shown in Fig. 5.

The operation is as follows: The free end *o* of the filling is brought from cop or bobbin *p* forward and around the nose of head *g*, being directed to the right side by tang *h*, as described. It is then brought back and through recess *i* by the end of tail *h*, thus forming a loop over gooseneck *f*. The tension is retained, and the loop of thread is thus drawn down and back along gooseneck *f* until it meets the curved portion of thread-guide *k*. As the distance is less from the outside of this curved portion than from the base of gooseneck *f*, the loop of thread slips down and out until it reaches the shortest point on the outside, as shown in Fig. 4. The outside wall of the shuttle being cut away to form the oval recess *n*, near the center of which is the point where the bight of thread lands, and as the thread-guide is flat and projects clear into this recess *n*, the loop of thread can be readily picked out with the dry fingers. It can then be passed under the end of the tang *l*, through recess *m* into tube *d*, or this can be neglected, and as the shuttle moves back and forth on the lay-beam the thread will be automatically drawn over the end of tang *l* and will land in the eduction-tube or eye *d*, where it is retained by tang *l* and remains until the filling of that particular cop or bobbin has run out.

I find that it facilitates the threading if an oblique slot *r* is cut in the side of slot *b* and

the opposite corner of said slot is beveled off, 65 as shown at *s*.

The purpose of slot *r* is that when the thread has been pulled along the guide *k* until it protrudes into recess *n* it falls into slot *r*, and when the thread is loosened by the fingers in 70 order to grasp it in the finger-recess *n* with some yarns there is a slight tendency to spring back out of reach, and this tendency slot *r* overcomes by holding the thread in place. Another object of slot *r* is to accentuate the 75 proximity of the outer end of eduction-tube *d* to the wall of slot *b* for the purpose explained on page 1, lines 75 to 82.

Instead of the head, with the tang just described, I can use a straight head, preferably 80 bent away from tube *d*, as shown in Fig. 6; but this is objectionable for the reason that if the operator loops the filling about the wrong side thereof, as can be done, the free end comes under the thread-guide *k* and the 85 fixed end comes over it and cannot be passed through tube *d*.

Instead of the form of tang shown at *l*, I can use the tang shown in Figs. 6 and 7 at *t*, which is an extension of a part of the wall of 90 tube *d* into a spiral over which the thread may be easily slipped. This form gives a better bearing-surface for the filling as it is run off the shuttle; but it does not keep the filling in tube *d* as well as the other form. 95

My device is cheaply made, as it consists, substantially, of a sheet of metal stamped out and bent into the desired shape and readily inserted into the shuttle. The woodwork of the shuttle is cut away very little and is therefore not weakened, as in some other devices. The guides and deflectors are so arranged that it is practically impossible for the filling to take any but the desired course around the gooseneck and out to the side opening, and 100 then it stops in its outside position, where it presents a loop which can be instantly picked out and the filling brought into position in the shuttle-eye. It can be operated with great 105 speed and without the operator even looking at the shuttle, as the filling is merely carried forward and then back by the hand and is then immediately picked off the side of the thread-guide. 110

What I claim as my invention, and desire to 115 cover by Letters Patent, is—

1. In a shuttle, a body having a cop or bobbin chamber, an extension thereof, and a passage between said extension and the outside of the shuttle-body about the shuttle-eye, 120 combined with a finger-recess about the outlet of the shuttle-eye, and a thread-guide adapted to conduct a loop of thread from said chamber through said passage well into said recess. 125

2. In a shuttle, a body provided with a cop or bobbin chamber, a recess forming an extension thereof, and a lateral opening from

said recess to the side of the shuttle, combined with a finger-recess about the outside of said opening, and a thread-guide adapted to conduct a loop of thread from said chamber-recess through the opening into said finger-recess.

3. In a shuttle, a body having a cop or bobbin chamber, a recess forming an extension thereof, and a lateral opening from said recess to the side of the shuttle, combined with a thread-guide adapted to conduct a loop of thread from inside said recess to a point outside said opening, and a recess about said point of outlet whereby the loop may be seized by the fingers of the operator.

4. In a shuttle, a body having a cop or bobbin chamber, a recess forming an extension thereof, and a lateral opening from said recess to the side of the shuttle, combined with a thread-guide inserted in said opening and recess and formed with an oblique guiding edge, a gooseneck and a head at the end of said gooseneck whereby a loop of thread may be conducted from said head inside the recess to the outside of said opening near the shuttle-eye, means for supporting the thread-guide, and a recess in the side of the shuttle about the point where the loop of thread stops whereby it may be picked off from the thread-guide by the fingers.

5. In a shuttle, a body having a cop or bobbin chamber, a recess forming an extension thereof, and a lateral opening from said recess to the side of the shuttle, combined with a thread-guide inserted in said opening and recess and formed with a slotted cylinder adapted to serve as a shuttle-eye, an oblique guiding edge, a gooseneck, and a head at the end of said gooseneck whereby a loop of thread may be conducted from said head inside the recess to the outside of said opening near the shuttle-eye, and a recess in the side of the shuttle about the point where the loop of thread stops whereby it may be picked off from the thread-guide by the fingers.

6. In a shuttle, a body having a cop or bobbin chamber, a recess forming an extension thereof, and a lateral opening from said recess to the side of the shuttle, combined with a thread-guide inserted in said opening and recess and made up of a slotted cylinder which serves as a shuttle-eye, a horizontal plate formed with an edge oblique to the axis of the shuttle and adapted to direct a loop of thread from the bottom of the recess to the outlet of the cylinder, a gooseneck formed by an oblique extension of said plate rising into said recess and provided at its free end with a head, over which the thread may be looped.

60 7. In a shuttle, a body having a cop or bobbin chamber, a recess forming an extension thereof, and a lateral opening from said recess to the side of the shuttle, combined with a thread-guide inserted in said opening and recess and made up of a slotted cylinder which

serves as shuttle-eye, a horizontal plate formed with an edge oblique to the axis of the shuttle and adapted to direct a loop of thread from the bottom of said recess to the outlet of the cylinder, a gooseneck formed by an oblique extension of said plate rising into said recess, and a head at the free end of said gooseneck arranged to almost touch the wall of said recess and provided with an oblique guiding edge whereby the thread naturally passes around a given side of said head.

8. In a shuttle, a body having a cop or bobbin chamber, a recess forming an extension thereof, a lateral opening from said recess to the side of the shuttle, and a shuttle-eye, combined with a thread-guide inserted in said opening and recess and made up of a plate provided with an oblique guiding edge adapted to guide the thread from said recess through said opening to the outside of the shuttle-eye, a gooseneck carried by said plate, a head carried by the gooseneck and so placed that its nose almost touches one wall of the recess, a tail carried by said head adapted to slope backward from said nose obliquely across said recess, and a tail-recess into which the free end of said tail enters.

9. In a shuttle, a body having a cop or bobbin chamber, a recess forming an extension thereof, and a lateral opening from said recess to the side of the shuttle, combined with a thread-guide inserted in said opening and recess and formed with a gooseneck, a head, and an oblique guiding edge, whereby a loop of thread may be conducted from said head inside the recess to the outside of said opening, near the shuttle-eye, means for supporting said thread-guide out of contact with the walls of said recess and opening, and means for allowing the thread to pass into the shuttle-eye and to prevent its getting out therefrom.

10. In a shuttle, a body having a cop or bobbin chamber, a recess forming an extension thereof, and a lateral opening from said recess to the side of the shuttle, combined with a thread-guide inserted in said opening and recess and made up of a slotted cylinder which serves as a shuttle-eye, a horizontal plate formed with an edge oblique to the axis of the shuttle and adapted to direct a loop of thread from the bottom of the recess to the outlet of the cylinder, a gooseneck formed by an oblique extension of said plate rising into said recess and provided at its free end with a head over which the thread may be looped, and a guide at the outlet of the cylinder adapted to permit the entry of the thread and to prevent its exit.

11. In a shuttle, a body having a cop or bobbin chamber, a recess forming an extension thereof, and a lateral opening from said recess to the side of the shuttle, combined with a thread-guide inserted in said opening and recess and made up of a slotted cylinder, a plate provided with an oblique guiding edge, a

gooseneck extension of said plate, a head at the free end of the gooseneck, a tang at the outlet of the cylinder, a recess into which the tang extends, and an eye at the junction 5 of the tang and cylinder adapted to present a curved surface to the thread as it is drawn out.

12. In a shuttle, a body having a cop or bobbin chamber, a recess forming an extension thereof, and a lateral opening from said recess 10 to the side of the shuttle, combined with a thread-guide inserted in said opening and recess and formed with a slotted cylinder adapted to serve as a shuttle-eye, an oblique guide integral with said cylinder in said opening, an 15 oblique gooseneck integral with said guide and rising into said recess, a head carried by said gooseneck having an oblique thread-guide adapted to direct the thread around one side of said head, and a tang at the outlet of said 20 cylinder across its slot and adapted to permit the thread to pass into the cylinder and to prevent its getting out.

13. In a shuttle, a thread-guide consisting of a slotted cylinder, a plate formed by an extension thereof, and provided with an oblique guiding edge, a gooseneck carried by said plate and forming an oblique angle therewith, a head carried by said gooseneck, and a tail carried by said head and extending backward 30 in an oblique direction from the nose thereof, combined with a tang at the end of said cylinder extending across the line of the slot in the cylinder.

14. In a shuttle, a body having a cop or bobbin chamber, a recess forming an extension thereof, and a lateral opening from said recess to the side of the shuttle, combined with a thread-guide, consisting of a slotted cylinder adapted to form a shuttle-eye, and suitable

guides formed integral with said cylinder and 40 adapted to guide the thread from said recess into said cylinder, and a pin driven through the body of said shuttle and said cylinder whereby said thread-guide is held in place.

15. In a shuttle, a body having a cop or bobbin chamber, a recess forming an extension thereof beveled at one corner and provided with an oblique recessed guide on one side, combined with an opening from the recess to the side of the shuttle, and a thread-guide 50c adapted to direct the thread from said recess through the opening and into the shuttle-eye as described.

16. In a shuttle, a body having a cop or bobbin chamber, a recess forming an extension 55 thereof, a finger-recess in the side of the shuttle, and an opening from the recess to the finger-recess, combined with a thread-guide consisting of a slotted cylinder adapted to form a shuttle-eye, a plate extended into the 60 opening and formed integral with said cylinder and provided with an oblique guiding edge, an oblique gooseneck carried by said plate and extended into said recess, a head carried by the gooseneck and arranged to almost touch one side of the recess, a tail carried by said head and extended obliquely 65 backward across said recess, a tail-recess into which said tail extends, a tang at the outlet of said slotted cylinder, a recess into which 70 said tang extends, and a curved bearing-surface at the junction of said tang and cylinder.

In testimony whereof I have affixed my signature in presence of two witnesses.

JAMES E. WELTON.
